US00D324001S

United States Patent [19]Kerr*Patent Number: Des. 324,001*Date of Patent:  Feb. 18, 1992*[54] COMBINED CLOCK FACE AND HANDS THEREFOR*[76] Inventor: Breene M. Kerr, 1200 Davinbrook, Oklahoma City, Okla. 73118*[] Term: 14 Years*[21] Appl. No.: 350,337*[22] Filed: May 11, 1989*[52] U.S. Cl. .... D10/126*[58] Field of Search .... D10/1-40, D10/122-132; 368/15-20, 228, 232, 238, 285, 280-282*[56] References Cited*U.S. PATENT DOCUMENTS

D. 317,028	8/1991	Bourquin	.....	D10/39
D. 318,810	8/1991	Bourquin	.....	D10/39
463,101	11/1891	Cory	.....
2,437,621	3/1948	Strate	.....	235/78
3,570,239	3/1971	Charles	.....	D10/31 X
3,703,804	11/1972	Appelberg	.....	368/19

3,721,083	3/1973	Jauch	.
3,825,181	7/1974	Banner	.....
3,902,309	9/1975	Torrence	.
4,014,163	3/1977	Wisser	.....
4,659,232	4/1987	Coster	.....
4,759,002	7/1988	Cash	.....
4,849,949	7/1989	Voth	.....

FOREIGN PATENT DOCUMENTS

37984	3/1909	Austria	.....
41143	9/1907	Switzerland	.....

Primary Examiner—Nelson C. Holtje
Attorney, Agent, or Firm—Laney, Dougherty, Hessin & Beavers

CLAIM

The ornamental design for a combined clock face and hands therefor, or the like, as shown and described.

DESCRIPTION

The FIGURE is a front elevational view of a combined clock face and hands therefor showing my new design. The dial and hands are of no appreciable thickness and the rear is flat, plain and unornamented.